AIR DASHPOT

Harvey N. Bliss, Windsor, Conn., assignor to Veeder-Root, Incorporated, Hartford, Conn., a corporation of Connecticut

Application March 8, 1954, Serial No. 414,575

5 Claims. (Cl. 188—95)

The present invention relates to dashpots for retarding or checking mechanical movements, and more particularly to an improved dashpot which is adapted to operate with a compressible fluid, such as air, as a motion-retarding medium.

Dashpots employing a compressible fluid as a motion-retarding medium have had limited application in the past, principally because the compressible medium must be compressed a substantial amount before it develops much resistance or retarding effect. This means that the piston or equivalent medium-compressing member of the dashpot has to be displaced a substantial distance in the cylinder or equivalent chamber containing the compressible medium before any substantial motion-retarding effect is developed. Such substantially unchecked displacement permits an excessive amount of substantially unrestrained travel of the piston relative to the cylinder which is obviously undesirable, and renders the dashpot unsuitable for many applications.

As a result of this difficulty, dashpots employing compressible fluids, such as air, have not been favorably regarded for many uses, even though they offer many advantages in comparison with dashpots filled with non-compressible fluids, such as oil. For example, air dashpots, unlike hydraulic dashpots, are relatively unaffected by temperature changes and also are superior from the standpoint of freedom from filling and leakage problems, cleanliness and reduced cost of manufacture.

The principal object of the present invention, therefore, is to provide an improved dashpot adapted to be filled with a compressible fluid, such as air, and in which unretarded movement of the fluid compressing member is substantially completely eliminated.

Another object is to provide a dashpot suitable for use with compressible fluids and in which the motion retarding force developed by the fluid medium extends throughout substantially the entire stroke length of the fluid compressing member.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing:

Figure 1 is a longitudinal sectional view of a dashpot constructed in accordance with the present invention, illustrating one extreme position of the parts thereof;

Figure 2 is a view similar to Figure 1, showing the other extreme position of the parts.

Referring to the drawing, a dashpot constructed in accordance with the present invention includes a casing or cylinder 2 which serves as a container for the motion retarding fluid, which may be a compressible fluid, and is preferably air. The cylinder is internally threaded at one end to receive an end plate 4 having an upstanding neck 6 which is provided with a bore 8 perpendicular

2

to the axis of the cylinder to receive a pin of an anchor or the like to which the cylinder may be secured, and about which it may be pivoted, if desired. The other end of the cylinder 2 is closed by an end plate 10 having an

outwardly extending neck 12 in which is provided an axially disposed throughbore 14 for accommodating a reciprocable piston rod 16. The piston rod 16 is preferably received in the bore 14 with a close sliding fit to prevent leakage of the cushioning fluid from the cylinder

10 2, and the outer end of the neck 12 is counterbored to receive a packing ring 18 of oiled felt or the like for lubricating the piston rod 16 and insuring a substantially leakproof connection between the rod and the cylinder. The outer end of piston rod 16 is provided with a bore

15 20 forming another pivotal connection for the dashpot. Supported for axial slidable movement in the cylinder

2 is a piston 26, which includes a support plate or disc 28, and a flexible washer 30 of leather or the like disposed on one side thereof. Preferably, the other side

20 of the support plate 28, opposite end plate 10, is shaped in a manner complementary to plate 10, so as to provide a good surface-to-surface mating contact therewith. The support plate 28 is of sufficient diameter to fully support the washer 30, but is freely slidable within the

25 cylinder 2. The support plate is provided at its center with a hollow sleeve 32 which slidably engages and is supported on the piston rod. The sleeve 32 is threaded at its outer end, as shown in Figure 2, and carries a nut 33 beneath which is retained a backing plate 34 which

30 serves to clamp the flexible washer against the support plate.

The washer 30 is of sufficient diameter so that, when enclosed within the cylinder, it has a longitudinally de-

35 pending rim or circumferential flange 38 which engages the inside wall of the cylinder with a sufficiently fluid-tight sliding connection to compress the fluid in the cylinder and retard or brake displacement of the piston in one direction, i. e. upwardly as shown in the drawing. On the other hand, when the piston is displaced downwardly in the cylinder, the flange 38 of washer 30 yields

40 sufficiently to allow the fluid to flow freely past the piston, and thus movement of the piston in this direction is substantially unretarded.

The end of the piston rod within the cylinder has a necked-down or reduced diameter portion 40, the junction of which with the remainder of the piston rod forms a tapered shoulder 41.

The sleeve 32 of support plate 28 is provided with a tapered counterbore 42 on its lower side which complements and is adapted to seat against the shoulder 41, thus preventing slidable movement of the piston rod 16 relative to the piston 26 in the upward

45 direction as shown in the drawing. The shoulder 41 is so located on the piston rod 16 as to space the piston from the end plate 10 of the cylinder, when the piston rod 16

50 is at its innermost extreme position as shown in Figure 2, a distance somewhat less than the full length of stroke of the piston rod 16. To normally hold the piston against the shoulder 41, and yet enable limited axial sliding movement of the piston rod 16 relative to the piston 26 in the

55 downward direction, there is provided between the piston and piston rod an axially resilient connection in the form of a compression spring 44, one end of which engages the outer end of the sleeve 32 and the other end of which

60 is retained by a washer 46 held on the end of the piston rod 16 by a snap ring 48 or the like.

To permit controlled flow of the dashpot fluid between opposite sides of the piston, and thereby enable regulation of the speed of piston travel, the piston is provided with a fluid bypass, which consists of a screw 50 threaded into

65 a hole provided in the support plate and having its head 52 received in aligned holes in the washer and the back-

70 ing plate. The screw 50 has a longitudinal bore 54, one

end of which is reduced in diameter to provide a metering bypass orifice 56 through which the fluid in the cylinder is adapted to flow as the piston is displaced axially of the cylinder. The bypass provides a control orifice which of course may be made adjustable or of any desired size to provide any desired degree of throttling of the bypass flow.

The operation of the dashpot will now be described. As previously described, the piston 26 is so located on the piston rod 16 as to be spaced from the end plate of the cylinder a distance somewhat less than the full stroke length of the piston rod when the rod is at its innermost position in the cylinder 2, as shown in Figure 2. Thus, when the rod 16 is withdrawn from the cylinder in moving toward its other extreme position, as shown in Figure 1, the movement of the piston 26 with the rod brings the mating surfaces of the piston 26 and end plate 10 of the cylinder into abutting or contacting relation somewhat before the piston rod reaches the end of its outward stroke. Since the bypass orifice 56 in the piston permits the fluid in the cylinder to flow from one side of the piston to the other, and since the piston 26 is constructed so that fluid in the cylinder may flow past the edge of the piston relatively freely during the outward stroke of the piston rod, it will be appreciated that the abutting and mating engagement of the piston 26 and end plate 10 will displace substantially all of the fluid from between the piston and end plate. The remaining portion of the outward stroke of the piston rod 16 after the piston 26 abuts the end plate 10 is accommodated by the compression of the spring 44, which insures that the piston will be maintained in tightly abutting and mated engagement with the end plate 10 to prevent fluid from re-entering therebetween through the bypass orifice. Provision of the axially yielding connection afforded by spring 44 also permits the rod 16 to be displaced the remainder of its stroke, relative to the neck 6, without danger of injury to any portion of the dashpot. Thus operation of the dashpot in the manner described can be obtained without the necessity of careful and exact regulation of the piston rod stroke length, to avoid inadvertent pulling of the end plate 10 out of cylinder 2, or other damage to the dashpot. The axially resilient connection provided by spring 44 also insures that any slight displacement of the piston rod 16 back into the cylinder 2, due to backlash in the equipment to which it is connected or for any other reason, will not displace the piston out of abutting engagement with the end plate and permit fluid to re-enter behind the piston.

With this arrangement, when the piston rod 16 is displaced back into the cylinder and the shoulder 41 engages the piston 26 and moves it away from engagement with the end plate 10, a partial vacuum is immediately formed between the piston 26 and end plate 10. The presence of this partial vacuum behind the piston creates a substantial pressure differential across the piston, even though the fluid in the cylinder on the front side of the piston has been compressed very little, or not at all. Thus a substantial retarding force is applied to the piston 26 at the very beginning of its displacement away from the end plate 10 and well before the development of any material retarding effect by compression of the fluid in front of the piston. Of course, as the piston is further displaced away from the end plate with the further displacement of the rod into the cylinder, fluid will flow through the bypass orifice 56 and into the space between the piston and end plate, and the inherent expansion of the fluid will rapidly reduce the vacuum. By the time the vacuum has been much reduced, however, the piston will have been displaced sufficiently far in the cylinder to compress the fluid on its front side enough to develop a substantial retarding effect for the piston rod in the usual manner.

It may thus be seen that, with a dashpot constructed and operating as above described, excessive free movement of the piston rod, or objectionable displacement

of the piston into the cylinder before any retarding effect is developed, is eliminated, and a substantial motion retarding force is applied to the piston right from the start of its displacement. This immediate retarding effect resulting from the vacuum developed behind the piston, together with the retarding force developed later on by the conventional compression of the fluid in front of the piston, insures an ample braking of the piston rod displacement throughout substantially the entire length of its stroke. As a result of this improved operation, dashpots employing a cheap and practical compressible fluid, such as air, may be used to advantage in installations where excessive free and unrestrained movement has hitherto made their use impractical.

While the present invention has been illustrated as applied to a dashpot in which the fluid is compressed only during movement of the piston in one direction, it will be obvious that the invention may also be employed in a dashpot of the type wherein the piston compresses the fluid and retards the piston rod displacement in both directions.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

35 I claim:

1. An air dashpot comprising an air cylinder having sealed end walls, a reciprocal piston rod extending through one end wall, said rod having a solid portion of reduced cross section at its inner end terminating in a radial shoulder spaced from the end of the rod, a piston slidably mounted on said portion for limited sliding movement axially of the rod toward and away from the shoulder, a spring on the rod fastened to the end of the rod and engaging the piston for biasing the piston toward said shoulder, said piston having a surface complementary throughout to said one end wall whereby substantially all of the air is displaced from between the piston and said one end wall when the piston abuts said one end wall, and means forming a continuously open but restricted fluid bypass through the piston.

2. An air dashpot comprising an air cylinder having sealed end walls, a reciprocal piston rod extending through one end wall, said rod having an imperforate portion of reduced cross section at its inner end, a single piston slidably mounted on said portion for limited sliding movement axially of the rod, said one end wall having a planar surface facing the piston, a spring between the rod and piston biasing the piston toward said one end wall of the cylinder, said piston comprising a plate having a planar surface complementary to said one end wall and a flexible washer mounted on the plate, said planar surfaces being coextensive to displace substantially all of the air between the piston and said one end wall when brought into abutment, means forming a restricted fluid bypass through the piston, and connecting means on the cylinder and piston rod.

3. An air dashpot for uniformly controlling the speed of oppositely moving elements comprising a cylinder closed at its ends and containing air, a reciprocable piston rod in said cylinder, a piston on said rod including a rigid disc of slightly less diameter than said cylinder and a flexible washer clamped against one side of said disc, said washer having a diameter normally larger than said cylinder so as to form within said cylinder a resilient peripheral flange extending axially away

from said disc and engageable with said cylinder during movement of said piston in one direction to compress the air therein, a continuously open but restricted fluid bypass in said piston connecting opposite sides thereof, said piston being positioned on said rod so as to abut said disc into contact with one end of said cylinder at the end of the stroke of said piston rod in a reverse direction opposite to said one direction, and a resilient connection between the piston and piston rod to permit overtravel of the piston rod, said disc having a surface complementary throughout to the opposed surface of said one end of said cylinder for displacing substantially all air from between the complementary surfaces of said disc and cylinder end at the end of the stroke in said reverse direction whereby disengagement of said piston from said cylinder end during the return stroke of said piston rod in said one direction creates a vacuum behind said piston for retarding movement of said rod.

4. An air dashpot for uniformly controlling the speed of opposite relatively moving elements comprising a cylinder having end walls, a piston disposed in the cylinder for sliding movement toward and away from one end wall of the cylinder, said piston having a surface which is complementary throughout to said one end wall so that when the piston abuts said one end wall substantially no air exists between the piston and the end wall, means forming a continuously open but restricted orifice to admit air between the piston and end wall to regulate movement of the piston away from said end wall, and means for connecting the cylinder and piston to oppositely relatively moving elements permitting limited relative movement of the elements after the piston and said one end wall engage.

5. In an air dashpot, a cylinder having end walls, a piston disposed in the cylinder for sliding movement toward and away from one end wall of the cylinder, said piston having an end face arranged to abut said one end wall of the cylinder at the limit of its travel toward said one end wall, said end face having substantially the same area as said end wall and being contoured throughout complementarily to said end wall so as to displace substantially all of the air therebetween and form a vacuum when the piston abuts said one end of the cylinder, a flexible washer attached to and carried by the piston in engagement with the side wall of the cylinder rearwardly of said end face of the cylinder to prevent the passage of air around the periphery of the piston as the piston is moved away from said end wall of the cylinder, a piston rod connected to the piston and extending through an end wall of the cylinder, and means forming a continuously open but restricted orifice to admit air between the piston and said end wall to regulate movement of the piston away from said end wall.
